W. H. SANBURN

PAPER ROLL TRACK FOR PAPER MACHINES

Filed Nov. 15, 1919

UNITED STATES PATENT OFFICE.

WILLIS H. SANBURN, OF SPRINGFIELD, MASSACHUSETTS.

PAPER-ROLL TRACK FOR PAPER MACHINES.

Application filed November 15, 1919. Serial No. 338,320.

To all whom it may concern:

Be it known that I, WILLIS H. SANBURN, a citizen of the United States of America, and a resident of Springfield, in the county 5 of Hampden and State of Massachusetts, have invented certain new and useful Improvements in Paper-Roll Tracks for Paper Machines, of which the following is a full, clear, and exact description.

10 The present application is directed to subject matter divided out of my copending application for Letters Patent for paper sizing apparatus, filed September 24th, 1915, Serial 52,357.

15 The invention specifically relates to improved means for shifting the roll of sized paper from my improved paper sizing machine or apparatus to a work table, track or bench positioned near the sizing machine or apparatus and normally separated therefrom by an open space, which may be bridged at will by operating the shiftable tracks provided for by my invention, herein described.

20 25 One of the objects of my invention is to provide a simple and practical shiftable track connection between a take up table, bench or track, and the sizing machine or apparatus, whereby a completed roll may be readily removed from the machine or apparatus without loss of time.

Another object of the invention is to provide a simple lock for securing the shiftable track in bridging position across the open 30 space between the take-up table or bench and the machine or apparatus, so that the extended tracks will constitute a firm support capable of sustaining the weight of the paper roll when moved across the tracks to the take-up table or bench.

40 With the above and other objects in view the invention comprises certain new and useful combinations, constructions and arrangements of parts, clearly described in the following specification and fully illustrated in the accompanying drawings, in which:—

45 Figure 1 is a plan view showing the shiftable tracks and their relation to the paper sizing machine disclosed in my copending application, identified above.

50 Figure 2 is a side elevation thereof.

Figure 3 is a detail side elevation showing one of the shiftable tracks in bridging posi-

tion connecting the table or take-up tracks with the machine or apparatus tracks, so 55 that the roll may be moved from the sizing machine to the take-up tracks.

Figure 4 is a detail transverse sectional view taken on line 3—3 of Fig. 3, looking in the direction of the arrow.

Figure 5 is a detail transverse sectional view showing one of the shiftable tracks in its lower position under one of the main take-up tracks.

Referring to the accompanying drawings, 65 A designates my improved paper sizing machine, which includes the supports B for the take up roll C, which is made up of the finished product. It will be apparent that the machine A may be of any character for 70 the purposes hereinafter described, in connection with the movement of the take-up roll from the machine or its supports B.

Owing to the great weight of the large 75 paper rolls it is desirable to eliminate lifting of the rolls as much as possible, and to substitute a rolling movement. To this end take-up tracks D and E are arranged in line with the roll supports B and upon the supports F. The take-up tracks D and E may 80 be in the form of a table or bench, or as shown, consist of parallel tracks with open spaces between.

Each of the tracks D and E is formed on its upper horizontal surface with a 85 groove g, providing parallel raised portions h and i, and below this groove portion there is an open channel or chamber j which receives the shiftable track G. This shiftable track is not as wide as the tracks D and E, 90 but it is formed with a groove k in its upper portion which is of the same width as the groove g of the tracks D and E.

Each shiftable track G is formed with a longitudinal recess g', extending along one 95 side thereof and providing a longitudinal shoulder g''. Each of the tracks D and E is equipped with a locking cam element I, which is journaled to the side wall of the chamber or channel j, and which includes a 100 cam member I and a handle m. The cam member I lies against the longitudinally recessed side face of the shiftable track and the handle m lies against the out side face of the fixed or take-up track.

105 Each track D and E is formed with an

opening *n* on its upper portion, which is located near the end thereof confronting the machine, and this opening extends on each side of the cam locking device, so that 5 the shiftable track may be elevated said cam locking position to the same horizontal plane as the fixed track, as shown in Fig. 3 and in Fig. 5, whereby the outer end of the shiftable track may be aligned with the 10 track section *K* located on the support *B* of the take-up roll.

In order to secure the shiftable track to the track section on the machine support *B*, I provide a stud or pin *o* on the outer end 15 of the shiftable track, which is designed to snugly fit in a socket *p* formed in the opposing end of the track section *K*.

The shiftable track is manually elevated by turning the locking cam through the 20 medium of the handle thereof, so that the outer end of the shiftable track will pass through the opening *n*, thus permitting the shiftable track to be bodily aligned with the take-up tracks and the track sections *K*, whereby 25 the take-up or finished paper roll may be readily shifted along said shiftable tracks to any desired point in the mill or elsewhere.

Having described my invention, I claim and desire to secure by Letters Patent:

1. The combination with a paper machine 30 including a take-up roll adapted to receive the finished product and companion take-up tracks normally spaced from the machine, of companion tracks slidable on said take-up tracks and adapted to bridge the space be- 35 tween said take-up tracks and machine, and means carried by the take-up tracks for elevating said shiftable tracks into horizontal alignment with the take-up tracks, so as to receive the take-up roll. 40

2. The combination with a paper machine including a take-up roll support having sockets therein, take-up tracks horizontally aligned with said sockets and providing channels therein, shiftable tracks normally disposed in said channels and provided with end studs adapted to fit into the sockets of said roll support, and cam members carried by said take-up tracks for elevating said shiftable tracks into horizontal alignment 50 therewith to permit said shiftable tracks to bridge the space between the take-up tracks and said roll support.

WILLIS H. SANBURN.
